UNITED STATES PATENT OFFICE.

DAVID M. THOMPSON, OF PROVIDENCE, RHODE ISLAND.

STEAM PLANT.

SPECIFICATION forming part of Letters Patent No. 593,703, dated November 16, 1897.

Application filed March 29, 1897. Serial No. 629,786. (No model.)

To all whom it may concern:

Be it known that I, DAVID M. THOMPSON, of Providence, in the county of Providence and State of Rhode Island, have invented 5 a new and useful Improvement in Steam Plants; and I hereby declare that the following is a full, clear, and exact description of the same, reference being had to the accompanying drawings, forming part of this specification.

In the generation of engine-power by the evaporation of water through the heat produced by the combustion of fuel, smoke, and particularly the black smoke discharged from 15 factory-chimneys, is the visible evidence of the imperfect combustion of the fuel in the furnaces.

Smoke consists of steam, vapors, usually 20 sulfurous, and unconsumed carbon. If the combustion in the furnace is practically complete, the smoke may be of a yellow or light-brown color, owing to the mineral matter, particularly sulfur, contained in the coal, but it will not be black, because it will not 25 contain the coloring-matter—namely, the unconsumed carbon. To secure the best results, it is essential that the combustion of the fuel in the furnace shall be perfect, and to insure this the volatile gaseous products 30 of the combustion of the solid fuel must be consumed before they enter the tubes of the boiler and become cooled.

The object of this invention is to secure 35 the perfect combustion of all the carbon in the fuel.

Another object of the invention is to utilize 40 the heat from the fire of one furnace while the gaseous products of combustion are passing to another furnace.

The invention consists in the peculiar and 45 novel construction of two connected furnaces, as will be more fully set forth hereinafter.

Figure 1 is a vertical view of two vertical 50 tubular steam-generators, showing the furnaces in section. Fig. 2 is an enlarged sectional view of the open passage connecting the two furnaces, showing the water-grate in the same.

Similar letters of reference indicate corresponding parts in both figures.

In the drawings, A and B indicate two vertical tubular steam-boilers.

C is a flue connecting the upper part of the boilers with a flue indicated in broken lines and extending to the chimney.

55

D D are two dampers pivotally secured in the flue C, and E E are two rods, each of which is connected with a crank on the shaft of the dampers D D and by which the dampers may be operated.

60

F F are two central columns forming the water-legs of each boiler.

G G are two dome-shaped furnaces, one under each boiler. These furnaces are much higher than the ordinary boiler-furnaces. 65 They are inclosed by the curved and inclined fire-brick lining H H and are connected by the fire-brick-lined passage I. The fire-brick lining is inclosed with the cellular casing K, containing water. The passage I has the water-grate L, supported on the pivots l l, which also form the inlet and outlet for the water which is forced through the passage formed in the grate L.

70 As the construction of the grate forms no part of the present invention, the grate is referred to as the "grate L" and for the purpose of this invention may be any of the ordinary forms of water-grate.

M is a door through which fuel is supplied 75 to the grate L, and N a door for the removal of the ashes. g g indicate the grates of the furnaces, and h h the fire-doors.

I will now more fully describe the operation 80 of furnaces in connection with the steam-boilers. When the fuel in the two furnaces has given up the volatile gases and the fire burns brightly without smoke, the dampers D D are open and the heated products of combustion ascend through the tubes of the vertical boilers to the uptake and through the flue C to the chimney in the usual manner, and when it becomes necessary to supply fresh fuel to the furnaces they are fired alternately. 85 If bituminous coal is used, one of the furnaces is supplied with the coal at a time when the other furnace has the bright fire which this fuel gives after the more volatile portions have been eliminated. Considering now that the right-hand furnace has reached that condition and the left-hand furnace requires to be fired, then, before firing, the grate L is 90 placed into the position shown in solid lines in Fig. 1, coke is placed on the grate L 95 and the fire-door N is closed. The grate L is then turned into the position shown in broken lines and the fire-door M is closed. The fire-door N is then opened and the coke is 100

through the opening M, the high temperature of the fire-brick lining of the passage ignites the coke, the damper D of the left-hand boiler is closed, and the other damper D is opened 5 wide. Coal is now thrown onto the fire of the left-hand furnace. The volatile carbon in the bituminous coal is liberated and rises into the upper part of the furnace, where, owing to the inward-curved dome-shaped fire-10 brick lining, the heat is intense, so that the gases are maintained at a very high temperature. As the draft on the left-hand boiler is shut off, the gases do not enter the tubes of the boiler, and there is consequently but lit-15 tle boiler-surface to cool the gases. It will be observed on examining Fig. 1 of the drawings that the arched furnace extends a con-20 siderable distance above the passage I, the upper part of which is about half-way be-25 tween the grate and the upper end of the furnace, and that this upper part of the furnace permits of the commingling and atomic mixture and expansion of the gases favored by the high temperature of this part of the furnace. As the draft on the left-hand boiler is closed and the draft on the right-hand boiler is wide open, the gases are drawn from the upper part of the left-hand furnace through the passage I and through the burn-30 ing coke or similar fuel on the grate L into and over the bright fire of the right-hand furnace and, completely burned, pass through the tubes of the right-hand boiler and from its uptake through the flue C to the chimney.35 During this time, which is not a long time, the boiler on the left is nearly as well supplied with heat and nearly as efficient as it is when the draft draws the heated products of combustion through the tubes of the boiler,40 because the heat of the furnace continues to rise up into the tubes. When the right-hand furnace requires to be fired, the operation is reversed and the grate L is placed into the position shown in broken lines in Fig. 1. As45 the carbon is all burned, no black smoke is discharged from the chimney and greater economy in the consumption of fuel is secured.

Having thus described my invention, I claim as new and desire to secure by Letters 50 Patent—

1. In a steam plant, the combination with two steam-boilers, of two furnaces connected by a horizontal passage and a grate in said passage, whereby, at the firing of one furnace, 55 the products of combustion may be passed

through the connecting-passage, ignited by fuel burning on the grate, and through the other furnace so as to consume the carbon in the products of one furnace and avoid smoke, substantially as described. 60

2. The combination of the following instrumentalities, viz: two vertical tubular steam-boilers, flues connecting the boilers with a chimney, dampers in the flues, two furnaces having inclined curved sides, a passage connecting the lower half of the two furnaces, and a grate, pivotally supported in the passage, whereby the products of combustion of one furnace may be passed through the connecting-passage into the other furnace to secure the more perfect combustion of the fuel, as described. 65 70

3. In combination with two vertical tubular boilers, flues connecting the boilers with the chimney, and dampers in these flues for controlling the draft, of two furnaces, one under each boiler, said furnaces having each a grate of larger diameter than the boiler and inclosed by a fire-brick lining having inclined curved sides, a fire-brick passage connecting 80 the two furnaces, a grate pivotally supported in the said passage and openings for supplying fuel to the furnaces and the grate in the connecting-passage, whereby the products of combustion of one furnace may be carried through 85 the passage, the other furnace and boiler by the draft to secure the more perfect combustion of the fuel, as described. 90

4. The combination in a steam plant with the two vertical tubular boilers A and B, having the flue C and the dampers D D for controlling the draft and the central column F F at the lower ends of the boilers, of the furnaces G G, one under each boiler, the grates g g and firing-doors h h and M, the inwardly curved fire-brick linings H H, the passage I forming a connecting-flue between the lower part of the two furnaces, the upper part forming disconnected dome-shaped chambers, the grate L and the cellular casing K inclosing 100 the lining of the furnaces and the passage; whereby the boilers may be alternately fired and the fuel more perfectly consumed, as described. 95 105

In witness whereof I have hereunto set my hand.

D. M. THOMPSON.
